UNITED STATES PATENT OFFICE.

JOHN E. KELLER, JR., OF LITCHFIELD, CONNECTICUT.

INFLATION-VALVE.

No. 923,359.

Specification of Letters Patent.

Patented June 1, 1909.

Application filed August 1, 1907. Serial No. 386,546.

To all whom it may concern:

Be it known that I, JOHN E. KELLER, Jr., a citizen of the United States, residing at Litchfield, in the county of Litchfield and

5 State of Connecticut, have invented new and useful Improvements in Inflation-Valves, of which the following is a specification.

My invention relates to inflation valves, and more particularly to valves adapted for 10 use in connection with pneumatic tires for motor vehicles and the like.

The primary object of my invention is to provide a device of this character which may be readily assembled and taken apart, 15 and which, when in position, shall be efficient and not liable to become deranged.

A further object of my invention is to provide, in a device of this character, convenient means for locking the valve tube 20 against rotation.

Further objects of the invention are to provide improved means for securing the valve tube in position in the felly, and to generally simplify and improve the 25 construction.

With the above and other objects in view my invention consists in the arrangement and construction of parts hereinafter described, and illustrated in the accompanying 30 drawings, in which:—

Figure 1 is a central longitudinal section, showing the preferred form of my improved valve complete, the same being attached to a tire. Fig. 2 is a transverse section thereof 35 on line 2—2 of Fig. 1. Fig. 3 is a transverse section on the line 3—3 of Fig. 1. Fig. 4 is a transverse section on the line 4—4 of Fig. 1, parts being omitted for greater clearness. Fig. 5 is a section on the line 5—5 of Fig. 1. 40 Fig. 6 is a perspective view of the valve tube shown in Fig. 1. Fig. 7 is a perspective view of the locking plug shown in Fig. 1. Fig. 8 is a central longitudinal section similar to Fig. 1, but on an enlarged 45 scale, showing a slightly modified construction. Fig. 9 is a view similar to Fig. 1, but showing a modified form of construction. Fig. 10 is a central longitudinal section similar to Fig. 1, but showing a still further 50 modification. Fig. 11 is a side elevation of the valve tube shown in Fig. 10. Fig. 12 is a perspective view of one of the parts shown in Fig. 10. Fig. 13 is a perspective view of the locking plug shown in Fig. 10. Fig. 14 55 is a central longitudinal section on an en-

larged scale showing some of the parts of Fig. 10 in slightly modified form. Fig. 15 is a perspective view of the locking washer hereinafter referred to.

Referring to the drawings in detail, and more particularly to Fig. 1, the construction therein illustrated comprises a tire tube 1 formed at its lower end with a flange 2, provided with concentric corrugations. The inner tube 3, of the tire is adapted to be 60 clamped between this flange and a similar corrugated washer 5 held in place by means of a nut 6 working on the screw threaded exterior of the tire tube. 4 represents the outer tube of the tire, and 7 the wheel felly. Fitting within the upper end of the tire tube is the valve tube 8. As clearly shown in Fig. 6 this tube is provided with external screw threads 9 at its upper end and with a shoulder 10, below which extends an enlarged portion having therein a central longitudinal slot 18, and, formed on the outside thereof, an annular groove 19. An expansible sleeve 11 of rubber, or similar material surrounds the tube 8 and fits against the shoulder 10, 70 and is held in position by a compression sleeve 12 which in turn, is secured in place by means of a nut 13 having a milled edge, screw threaded on to the upper portion 9 of the valve tube. By reference to Fig. 1 it 75 will be seen that by screwing down this nut 13 the sleeve 12 is caused to impinge against the expansible sleeve 11 and cause the same to swell or bulge, thereby forming an air tight joint between the valve tube and tire tube, and at the same time, securing the two tubes together by frictional engagement, so as to prevent accidental displacement.

In Fig. 8 I have illustrated a slightly modified form of the compression sleeve and 80 nut. By reference to this figure it will be seen that I form the compression sleeve 112 with a radial flange at its upper edge 114, and form, in the nut 113, a kind of socket which embraces this flange. Thus the two 100 parts 112 and 113 are swiveled together and prevented from separating when the valve is taken apart. This figure also illustrates the bulging of the expansible sleeve 11 due to the pressure.

As shown in Figs. 2 to 5 inclusive the tire tube 1 is formed with flat sides 1^a as is usual in this art, and the locking washers are formed so as to fit these flattened sides and be prevented from rotating. The improved 110

means which I prefer to use in order to hold the tire tube against rotation relative to the felly consists of a washer 29, embracing the tire tube and formed on its under face, where 5 it comes in contact with the felly, with a series of radial serrations or teeth. A nut 28 screw threaded on to the tire tube, serves to press the washer 29 into engagement with the felly and thus secure the parts in position. Slipped loosely over the tire tube and enveloping the nut 28 and washer 29, is a soft rubber bushing 27. A washer 25, carrying a packing ring 26, is adapted to overlie this bushing, and the cover cap 24, 10 screwed securely over the tire tube, is adapted to bear against the packing ring 26 and thereby force the bushing 27 into close engagement with the felly 7, thus forming practically a dust and water proof joint. Within 15 the valve tube 8 is disposed the valve 14, carried by the valve stem 15, which extends practically the entire length of the valve tube. Surrounding the lower end of this valve stem 15 is a spring 17, bearing at one end 20 against the valve and at the other end against the top of the locking plug 20. As clearly shown in Fig. 7 this locking plug consists of a hollow cylindrical body, provided with a pair of up-standing lugs or arms 21, adapted 25 to fit into the slot 18 of the valve tube 8. The locking plug 20 is also provided with an indentation 22. This locking plug fits, as shown in Fig. 1, into the lower portion of the tire tube, and after being inserted, the tube 30 is upset by means of a punch, as shown at 23 in Fig. 5, thereby forcing the metal into the indentation 22 of the locking plug and thus securing it in position. It is evident therefore that since the bifurcated portion of the 35 valve tube embraces the lugs 21 on the locking plug, the valve tube will thus be held against rotation relative to the tire tube, but may be readily withdrawn therefrom longitudinally. The purpose of the annular 40 groove 19 is to prevent the valve 14 from dropping out of the valve tube when the parts are separated. As shown in Fig. 1 the groove 19 forms a corresponding annular rib within the valve tube, which is of such 45 size as to prevent the valve readily slipping past the same, but the resiliency of the split portion of the tube permits the valve to be forced past the rib when it is desired to remove the same. The usual air cap 16 is 50 fitted to the upper end of the valve tube.

Referring now to Fig. 9 it will be seen that the tire tube there illustrated is of slightly different form. Besides being externally screw threaded, its entire length, it 55 is internally screw threaded a short distance at its upper end to receive a locking sleeve 43. The valve tube 38, provided at its upper end with a screw threaded portion 39, is also formed with an annular collar 40 against which the locking sleeve 43

bears. Between the lower side of this collar 40 and an annular shoulder 42 formed on the inside of the tire tube, a packing ring 41 is adapted to fit. It is obvious that the pressure exerted by the locking sleeve 43, 70 upon being screwed up, secures the parts together with a practically air tight joint at the packing ring 41. The valve, valve stem, spring, and locking plug are constructed and arranged substantially the same as in 75 Fig. 1.

Referring now to Fig. 10, I have illustrated a further modification which presents several points of difference over the types of construction above described. The valve 80 tube 68 is adapted to be secured in position by means of a locking sleeve 73 which bears against a shoulder of said tube and embraces the tire tube, and engages with the external screws threads thereon. A packing ring 71, 85 similar in construction and operation to the packing ring 41 illustrated in Fig. 9, is provided, and an air tight joint is formed between this ring and the shoulder 72 formed in the tire tube 61. The valve tube however, illustrated in Fig. 10, and more clearly shown in Fig. 11, is relatively shorter than that shown in the other figures and is adapted to coöperate at its lower end with an additional element which I shall designate a 90 spring holder. This device is shown clearly in Fig. 12 and comprises an annular flange 86 which snugly fits the interior of the tire tube and from which depends a lug 87 adapted to be embraced by the arms 81 carried by the locking plug 80. This locking plug 80 is provided with an indentation 82, as clearly shown in Fig. 13, and has the same function as the locking plug illustrated in Fig. 7. Referring again to Fig. 105 12 it will be seen that above the flange 86 extends a pair of arms 89, carrying at their upper end a ring 88. It will be seen that this ring 88 is of smaller diameter than the flange 86, and is adapted to fit within 110 the valve tube 68, while the arms 89 are adapted to lie within the slot 78 formed in the valve tube. The ring 88 is of such diameter that it may be forced into the valve tube past the annular rib 79 formed 115 therein, and the parts are so proportioned that the spring holder will not slip out accidentally, but can only be withdrawn from the valve tube by exerting considerable force. A spring 77 fits within the ring 88 120 and rests upon the flange 86 while, at the same time, it embraces the valve stem 75; thus the valve is held upward against its seat, while the spring holder is forced downward by the spring so that the lower edge 125 of the ring 88 abuts against the rib 79. (See Fig. 10).

It will be seen that in Fig. 10 the valve stem is screw threaded at both ends, and at the upper end a hollow thumb screw or cap 130

76 is screwed over the end thereof. The function of the screw threads on the lower end of the valve stem is illustrated in Fig. 14. In case it is desired to remove the valve 5 and spring holder from the valve tube, the valve tube is first removed from the tire tube by releasing the locking sleeve 73. Then by unscrewing the cap 76 from the upper end of the valve stem and attaching 10 it to the lower end thereof as shown in Fig. 14 the valve and spring holder assembled may be readily withdrawn from the lower end of the valve tube. Thus inspection and repairs are readily accomplished without 15 danger of losing or displacing any of the smaller parts. In the form of valve shown in Fig. 10 the cap or cover 84, instead of engaging directly with the tire tube, engages with a screw threaded nut 85 which, in turn, 20 is fitted to the tire tube. This construction is designed in order to permit the use of the locking sleeve 73.

While I have shown and described several modifications of my invention it is obvious 25 that they all contain the same general idea, namely, the provision of a locking plug for securing the valve tube and tire tube against relative rotation, while, at the same time, permitting their ready separation. It is to 30 be understood also that the locking washer 29 and rubber bushing 27 shown in Fig. 1 are equally applicable to the constructions shown in Figs. 9 and 10. In this connection it may be noted that the resiliency of 35 the bushing 27 exerts a pressure against the end of the cover cap 24 and thus frictionally holds the same against becoming loosened, owing to vibration. The bushing 27 therefore serves a double purpose.

40 In assembling any of the forms of my improved valve it may be seen that it is necessary for the slot in the valve tube to properly fit the lugs on the locking plug before the valve tube can be inserted sufficiently far in the tire tube to permit of 45 securing it therein. By this means, all danger is eliminated of wrongly assembling the parts, for with my construction, it is impossible to secure the valve tube within the 50 tire tube unless the packing rings are properly seated. I have thus provided a valve which may be assembled in the dark without fear of any error being made, since the valve tube is simply slipped into the tire 55 tube and turned until it drops into position, when the securing means can be adjusted.

It will thus be seen that I have provided a very simple and efficient valve construction, and it is thought that the many advantages thereof will be readily appreciated 60 by those skilled in the art.

What I claim is:—

1. In combination, a tire-tube, a valve-tube fitting therein, and a locking plug extending longitudinally of, and secured in 65

said tire-tube and detachably connected with said valve tube, whereby the parts are held against rotation.

2. In combination, a tire-tube, a valve tube fitting therein, a locking plug rigidly secured within said tire-tube, and extending longitudinally thereof and means detachably connecting said locking plug and valve-tube.

3. In combination, a tire-tube, a valve tube fitting therein, a locking plug secured in and extending longitudinally of said tire-tube, and held against movement in any direction, and means connecting said valve tube and locking plug, such means holding 80 said parts against relative rotation, but permitting the free movement of the valve tube in direction of its length.

4. In combination, a valve tube, having a valve seat, a valve-stem extending through 85 said tube and carrying a valve co-operating with said seat, and yieldable means formed from the material of said valve tube for engaging said valve and preventing it being accidentally dislodged from the tube. 90

5. In combination, a valve tube, a valve seat formed therein, a projection formed on the inner wall of said tube, and a valve having free movement between said seat and said projection, but capable of being forced 95 past said projection.

6. In combination, a valve tube, a valve therein, and means integral with said tube for preventing the accidental separation of 100 said parts while permitting them to be readily disconnected.

7. In combination, a tire-tube, a valve tube fitting therein, means for rigidly locking said parts against relative rotation only, and additional means for holding said parts 105 against relative longitudinal movement by friction only.

8. In combination, a tire-tube, a valve tube fitting therein, an expansible sleeve surrounding said valve tube, and means for 110 exerting pressure on said sleeve, so as to cause it to expand and grip the interior of said tire-tube, and thus hold the valve tube against longitudinal movement.

9. In combination, a tire-tube, a valve tube fitting therein, an expansible sleeve surrounding said valve tube, and a nut screw threaded onto said tube, and serving to exert a pressure on said sleeve and expand the same, and cause it to engage the said tire 120 tube.

10. In combination, a tire-tube, a valve tube fitting therein, an expansible sleeve surrounding said valve tube and in contact with said tire-tube, a compression sleeve 125 bearing upon said expansible sleeve, and a nut, screw threaded onto said valve tube, and bearing against said compression sleeve.

11. In combination, a tire-tube, a valve tube fitting therein, an expansible sleeve sur- 130

- rounding said valve tube and adapted to be forced against said tire-tube, and means for expanding said sleeve, said means comprising a compression sleeve bearing against 5 said expansible sleeve and provided with an annular, radial flange, and a nut, screw threaded onto said valve tube and provided with a socket adapted to embrace said radial flange.
- 10 12. In combination, a tire-tube, means for securing the same to a wheel felly, a cover cap screwed on to said tube, and a resilient bushing surrounding said tube, enveloping

said securing means, and held in position against the wheel felly by means of pressure 15 exerted thereon by said cover cap, whereby said cap is held against accidental displacement by the friction caused by said resilient bushing.

In testimony whereof I have hereunto set 20 my hand in presence of two subscribing witnesses.

JOHN E. KELLER, JR.
